(57) **CLAIM**

I claim the ornamental design for a sheet with pattern element for an absorbent article, as shown and described.

DESCRIPTION

FIG. 1 is a top view of a first embodiment of a sheet with pattern element for an absorbent article; and,

FIG. 2 is a top view of a second embodiment of a sheet with pattern element for an absorbent article.

The broken lines surrounding the drawings depict the boundaries of the claim and form no part thereof.
